Primary Examiner — George D. Kirschbaum*Assistant Examiner* — Darcey E Gottschalk(74) Attorney, Agent, or Firm — Birch, Stewart, Kolasch & Birch, LLP(57) CLAIM

The ornamental design for a cup holder, as shown and described.

DESCRIPTION

FIG. 1 is a perspective view of a cup holder showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a view showing an expanded state thereof; and,
FIG. 9 is a view showing a use state thereof.

In the drawings, the broken lines show portions of a cup that depicts environment and forms no part of the claim.
